S.E. Parrish,
Floor Clamp,

No 10,061.

Patented Sep. 27, 1853.

UNITED STATES PATENT OFFICE.

STEPHEN E. PARRISH, OF NEW YORK, N. Y.

CLAMP FOR LAYING FLOORS.

Specification of Letters Patent No. 10,061, dated September 27, 1853.

To all whom it may concern:

Be it known that I, STEPHEN E. PARRISH, of the city, county, and State of New York, have invented a new and useful Machine for 5 Matching or Laying Down Flooring-Boards; and I do hereby declare the following to be a full description of the same.

The nature of my invention consists in making a brace having a forked end, with 10 shoulder pieces attached to the underside thereof, so as to straddle one of the flooring beams, in combination with a screw working at right angles to the braces, and having on it a ratchet wheel and lever and pawl 15 for working up the screw against the edge of the plank. But to describe my invention more particularly I will refer to the accompanying drawings, the same letters in the drawing referring to the same parts 20 wherever they occur.

The figure is a perspective view of the machine, showing by the red lines one of the flooring beams and the plank.

Letter A, A, is the brace, made of iron 25 and of suitable strength for the purposes required. The outer or front end of this brace is curved out, so as to form two legs B¹, B², having on their lower sides shoulder pieces C¹, C², for the purpose of straddling 30 the flooring timber, as shown by the red lines D, and by their opposite action, when pressed against by the screw, holding firmly to it as a resisting point to the action of the screw. Transversely of the brace is ar- 35 ranged a box E, which may be made adjustable on working on a center as convenience may require. Through this box a screw F, works, having at one end a small wheel G, for the convenience of working up or back

the screw, and at the opposite end, a platen 40 or head piece H, secured to it by means of a box J, having pins in it so as to work in a groove on the end of the screw to allow it to turn freely while the platen or head piece remains firmly and stationary against the 45 edge of the flooring boards K, as seen by the red lines x x. On the screw is arranged a ratchet wheel L, which is operated by a lever M, having two pawls N¹, N², attached to it for the purpose of turning up or back 50 the screw for forcing the flooring boards in their places. The operation of the machine is that when the claw end of the brace is ad- justed over the beam and the screw worked up, so that the platen on the end of it presses 55 against the edge of the flooring boards, the handle end of the brace is forced back causing thereby the claws at the opposite sides of the beam to hold or clamp firmly against it, and as the screw is continued to be worked 60 up binds it so as to prevent the possibility of slipping, and thereby obtain a foot hold for the screw to act against it, equal always to the power of the screw.

Having now described my invention I will 65 proceed to state what I claim and desire to secure by Letters Patent.

What I claim and desire to secure is—

The use of the brace having clawed ends 70 for acting at opposite sides of a beam in combination with a screw working at right angles to the same substantially in principle of construction and operation as set forth.

S. E. PARRISH.
